(57) CLAIM

The ornamental design for a bag holder, as shown and described.

DESCRIPTION

FIG. 1 is a perspective view of the bag holder of the present invention;

FIG. 2 is a top view of the bag holder shown in FIG. 1;
FIG. 3 is an elevational front view of the bag holder shown in FIG. 2;

FIG. 4 is an elevational rear view of the bag holder shown
in FIG. 2;

FIG. 5 is a bottom view of the bag holder shown in FIG. 2;
FIG. 6 is an elevational right side view of the bag holder shown in FIG. 2; and,

FIG. 7 is an elevational left side view of the bag holder

The broken line showing of a bag in FIG. 1 is for illustrative purposes only and forms no part of the claimed design.
